UNITED STATES PATENT OFFICE

138,315

DESIGN FOR A WOMAN'S HAT FRAME

Max Gross, Buffalo, N. Y., assignor to Chic-Maid
Hat Manufacturing Co., Inc., Buffalo, N. Y., a corporation of New York

Application May 12, 1944, Serial No. 113,559

Term of patent 3½ years

(Cl. D3—13)

To all whom it may concern:

Be it known that I, Max Gross, a citizen of the United States, residing at Buffalo, in the county of Erie and State of New York, have invented a new, original, and ornamental Design for a Woman's Hat Frame, of which the following is a specification, reference being had to the accompanying drawing, forming part thereof.

In the accompanying drawing:

Fig. 1 is an end elevational view of a woman's hat frame showing my new design.

Fig. 2 is a top plan view thereof, viewed from the upper left of Fig. 1.

Fig. 3 is a rear elevational view thereof.

The opposite ends of the woman's hat frame are substantially identical.

I claim:

The ornamental design for a woman's hat frame, as shown and described.

MAX GROSS.
